UNITED STATES PATENT OFFICE

2,454,300

OVERHEAD SUPPORT FOR MILKERS

Henry B. Babson, Chicago, Ill., assignor to Babson Bros. Co., a corporation of Illinois

Application August 30, 1943, Serial No. 500,509

11 Claims. (Cl. 31—58)

1

This invention relates to an overhead support for a milker, and more particularly to improved means for supporting a suspended milker in operative position beneath a cow.

One feature of this invention is that it provides improved supporting means particularly designed for supporting a suspended milker in operative position beneath a cow in a parlor stall; another feature of this invention is that it permits convenient adjustment, from one side of the stall, of the position of the milker in the stall, and the amount of forward pull on the milker when it is milking; still another feature of this invention is that the supporting means does not interfere with the entrance and exit of the cow from the parlor stall; yet another feature of this invention is that the carrying member and milker may be conveniently placed beneath the cow in an appropriate vertical position; and a further feature of this invention is the provision of improved adjustable connecting means at each end of the carrying member. Other features and advantages of this invention will be apparent from the following specification and the drawings, in which:

Figure 1 is a perspective view of a parlor stall having one embodiment of my improved supporting apparatus associated therewith; Figure 2 is a transverse vertical sectional view of the stall, along the line 2—2 of Figure 3; Figure 3 is a fragmentary sectional view along the line 3—3 of Figure 2; Figure 4 is a partial top view of a parlor stall equipped with another form of my overhead supporting apparatus; and Figure 5 is a partial side elevational view of the upper end of the stall and of the supporting apparatus.

Suspended milkers have a number of advantages over other types of machines for milking cows, and a large proportion of the milkers now being commercially sold are of the suspended type. Such a milker comprises, as its principal parts, a bucket, a lid, a pulsator, four teat cups, and the rubber inflations and tubes necessary to render the combination operative; and the entire combination is suspended beneath the belly of the cow, slightly forward and below the udder to which the teat cups are connected. Such a milker will not be described more fully here since it is well known and in commercial use. Reference may be had to McCornack Patent No. 1,859,213 of May 17, 1932, and to other issued patents, for a more complete description of such suspended milkers and of the way in which they are conventionally supported.

Such milkers are generally supported beneath

2

the cow by an arrangement which comprises a surcingle strap thrown across the back of the cow and having its ends hanging down on each side of the cow, and a carrying member in the form of a spring steel rod extending across from one side to the other beneath the belly of the cow. As explained in the above-mentioned patent, it is desirable to push the top of the strap somewhat forward on the cow's back, and to have the lower ends of the surcingle and the carrying member relatively free to move, so that there is a forward as well as downward pull upon the teats during milking, accompanied by a dynamic or surging action providing an intermittent downward and forward pull and tug on the teats.

Such a suspension has to be thrown over the back of each cow which is milked, however, and slid around and back and forth to get the proper position for milking. When the cows are brought from their regular stalls to parlor stalls, it is desirable to avoid the necessity of putting a surcingle on and off each cow as it is milked. Means particularly designed for supporting a suspended milker in operative position in a parlor stall is shown in my earlier Patent No. 2,136,228, which issued November 8, 1938; but such a support comprises a swinging arm extending in from one side of the stall.

I have more recently devised and am here dis-
30 closing and claiming an overhead support for a milker, particularly designed for use with a parlor stall, this overhead support having certain advantages over previous supporting arrangements. In general, this new overhead supporting arrangement comprises supporting means mounted on the top of a parlor stall and movable longitudinally thereof, this means being longitudinally movable from one side of the stall and having suspension elements depending therefrom on each side of the 40 cow and carrying the ends of a carrying member extending beneath the belly of the cow and adapted to have the milker hooked thereon.

Referring now more particularly to the embodiment of my invention illustrated in Figures 45 1, 2 and 3, a parlor stall is shown as comprising four main corner posts 10a—d connected by longitudinal and transverse rod members, the two upper longitudinal rod members being here identified as 11a and 11b. The back end of the stall 50 is provided with a gate 12 adapted to be swung open to permit the cow to enter the stall; and a gate 13 in the forward portion of the stall is adapted to be opened to permit the cow to leave the stall after milking. Stanchion members 14a 55 and 14b are provided, the stanchion member 14b

being mounted on and movable with the gate 13. After one cow has been let out of the stall, the gate 12 is opened and the next cow driven in until her neck is in juxtaposition with the stanchion member 14a whereupon the gate 13 is closed and locked by any appropriate means, the cow then being held in desired position by the stanchion members. The front end of the stall is generally provided with a feed trough accessible to the cow when she is held by the stanchion members.

In order to support the suspended milker in operative position beneath the cow, supporting means extends across the top of the stall, this being shown as comprising the beam member 15 resting on the top members 11a and 11b of the stall. Annular elements 16 and 17, which may be formed of strap iron, encircle the member 15 near each side of the stall, these carrying depending elements 18 and 19 here shown as rope, steel cable, or other flexible means of generally circular cross section. Near the lower ends, each of these depending elements is provided with a plurality of spaced supporting members identified as 18a—d and 19a—d, these being here shown as steel balls spaced about two inches apart. A carrying member 20, in the form of a steel rod with a central depression 20a, into which the handle of the milker is hooked, extends across beneath the belly of the cow. This carrying member is provided with hook portions 20b and 20c at its ends, these being adapted to be hooked around the rope or cable just over one of the supporting members or balls.

The beam or supporting member 15 is provided with manual operating means at one end, these being here shown as the spokes 21a—d, so that the member 15 may be moved longitudinally of the stall (and thus of the cow) by turning it. In order to maintain the member 15 in the desired position on top of the stall members 11a and 11b, and in order to ensure equal movement of both ends of the member upon rotation of the end carrying the spokes, maintaining means is provided. This is shown as comprising ropes 22 and 23. Each of these ropes is fastened at the back end of the stall, extends along generally parallel to one of the upper longitudinal rod members (as the rod member 11a), is looped around the supporting member 15, and then extends to and is fastened at the front end of the stall. Rotation of the member 15 can thus be effected from one side of the stall by use of the spokes 21, and synchronized forward or backward movement of the suspension elements 18 and 19 will result. The transverse member 15 is preferably polygonal in shape, being here shown as square, to prevent undesired movement after it has been adjusted to the proper position. Turning the member 15 until one of its flat sides is in engagement with the upper stall members 11a and 11b provides enough resistance to backward movement to keep the member 15 from moving during the milking operation.

When a cow is being brought into the stall and the milker and the carrying member 20 are removed therefrom, the cow is driven in until her neck is positioned between and engaged by the stanchion members 14, as previously described. The operator (who stands on the same side of the stall as the spokes 21) then reaches under the cow with the carrying member 20, hooking the far end into an appropriate vertical position on the suspension element 19, and then hooking the near end similarly on the suspension element 18. This can be very quickly and easily done, as the carrying member 20 is rigid and there is no

difficulty in slipping the hook end 20c around the suspension element 19 immediately above one of the balls. As may be best seen in Figure 2, the hooked ends of the carrying member have a slight angle so that after they are once hooked in they tend to remain in place. The milker is then hung on the carrying member and properly positioned just in front of the udder through forward or backward movement of the member 15 by use of the handles 21. When the teat cups have been slipped up over the teats and the milker is operating, the member 15 may be further adjusted forward or back to secure the desired amount of forward pull during the milking operation. A representative position of the parts, during milking, is shown in dotted lines in Figure 1, the member 15 preferably being held forward of the position of the carrying member 20 when the milker is connected to the teats, so that the suspension elements 18 and 19 assume a definite angle, as shown, providing a forward pull on the milker. The provision of the supporting members 18a—d and 19a—d, in combination with the hooked ends of the carrying member 20, enables not only convenient and quick placement of the carrying member in operative position but also easy and quick vertical adjustment of the position of the milker to secure the best milking operation on different cows.

Referring now more particularly to Figures 4 and 5, only part of the parlor stall is shown, the stall being otherwise similar to that shown in Figure 1. In this case the upper longitudinal rod members are identified as 41a and 41b, these being again supported by corner posts 40a, 40b, etc. Immediately beneath the longitudinal members 41a and 41b, and parallel to them, are threaded shaft members 42a and 42b. At the back end of the stall these shaft members make bevel gear connection with a cross shaft 43 provided with a crank handle 44 at one end, so that the threaded shafts 42a and 42b are similarly rotated from one side of the stall by operation of the crank handle. Mounted on each of the shafts 42a and 42b are supporting means in the form of nuts here identified as 45a and 45b, these making threaded connection with the shafts 42a and 42b. These nuts have upwardly extending portions extending on each side of the longitudinal rods 41a and 41b, these rods serving as guides permitting longitudinal but preventing rotational movement of the nuts. Accordingly, operation of the crank handle 44, by rotating the shafts 42a and 42b, effects simultaneous longitudinal movement of the nuts 45a and 45b. The pitch of the thread on the shafts 42a and 42b is preferably small enough to prevent undesired movement of the supporting means 45a and 45b, so that they remain in the position to which they are adjusted even though there is a considerable component of backward pull exerted on them during milking.

The supporting means 45a and 45b have depending from them suspension elements, as the element 46, which are similar to the suspension elements 18 and 19 more fully shown and described earlier; and the suspension elements in this latter form of my invention are again provided with spaced supporting members near their bottoms adapted to be engaged by hook ends on the carrying member 41 adapted to extend beneath the belly of the cow.

While I have shown and described certain embodiments of my invention, it is to be understood that it is capable of many modifications.

Changes, therefore, in the construction and arrangement may be made without departing from the spirit and scope of the invention as disclosed in the appended claims.

I claim:

1. Apparatus for supporting a suspended milker from above a cow, including: a stall adapted to receive the cow; supporting means mounted on the top of the stall and movable longitudinally thereof, this means comprising a member extending across the top of the stall and provided with manual operating means on one end; means for maintaining the supporting means in desired relation with the top of the stall; suspension elements depending from the supporting means at each side of the cow; and a carrying member extending beneath the cow, this member being carried by said elements and being adapted to carry the milker.

2. Apparatus of the character claimed in claim 1, wherein the supporting means is a polygonal member.

3. Apparatus for supporting a suspended milker in desired relation to a cow, including: a carrying member extending beneath the cow and adapted to carry the milker, said carrying member being rigid whereby it can be manipulated at both ends from one end only; and separate suspension means depending at each side of the cow and connected to the ends of the carrying member, each of said two connections being adjustable for connection at different vertical positions of the suspension means.

4. Apparatus for supporting a suspended milker in desired relation to a cow, including: a carrying member extending beneath the cow and adapted to carry the milker; and separate suspension means depending at each side of and free of the cow and connected to the ends of the carrying member, the suspension means being provided, at both sides of the cow, with a plurality of spaced supporting members, and the cooperating end of the carrying member being provided with hook means adapted to engage any one of said supporting members, said carrying member being rigid whereby it can be manipulated at both ends from one end only and be selectively connected at different vertical positions of the suspension means.

5. Apparatus for supporting a suspended milker from above a cow, including: supporting means located above and free of the cow; suspension elements depending from the supporting means at each side of the cow, each element being provided, near its lower end, with a plurality of spaced supporting members; and a carrying member extending beneath the cow and adapted to carry the milker, each end of the carrying member being provided with hook means adapted to engage any one of said supporting members, said carrying member being rigid whereby it can be manipulated at both ends from one end only.

6. Apparatus for supporting a suspended milker from above a cow, including: supporting means located above the cow; suspension elements depending from the supporting means at each side of the cow, said suspension elements being flexible and having a generally circular cross section, each element being provided, near its lower end, with a plurality of spaced supporting members in the form of balls; and a carrying member extending beneath the cow and adapted to carry the milker, each end of the carrying member being provided with hook means adapted to engage any one of said supporting members.

7. Apparatus for supporting a suspended milker in desired relation to a cow, including: a carrying member extending beneath the cow and adapted to carry the milker; and separate suspension means depending at each side of the cow and connected to the ends of the carrying member, the suspension means being provided, at at least one side of the cow, with a plurality of spaced supporting ball-members and the cooperating end of the carrying member being provided with hook means adapted to engage any one of said supporting members.

8. Apparatus for supporting a suspended milker from above a cow, including: a stall adapted to receive the cow; separate supporting means mounted on each side of the stall and movable longitudinally thereof; means operable from one side of the stall for effecting simultaneous longitudinal movement of the supporting means, this means comprising horizontal shaft members on each side of the stall making threaded engagement with the supporting means; suspension elements depending from the supporting means at each side of the cow; and a carrying member extending beneath the cow, this member being carried by said elements and being adapted to carry the milker.

9. Apparatus for supporting a suspended milker from above a cow, including a cow-receiving stall having along each of its sides at the top a longitudinally extending rod member; supporting means comprising a cross-member extending across the top of the stall and movably mounted on said rod members for longitudinal movement therealong; means for moving said cross-member along said rod members; suspension elements depending from the supporting means at each side of the cow; and a carrying member extending beneath the cow, this last mentioned member being carried by said suspension elements and being adapted to carry the milker, each suspension element being provided with a plurality of spaced means for engaging the cooperating end of the carrying member, and said apparatus being provided with means for insuring equal movement of the ends of the cross-member along said rod members.

10. Apparatus for supporting a suspended milker, including: a stall adapted to receive a cow; supporting means mounted at the top of the stall and movable longitudinally thereof; suspension elements immovably connected to the supporting means and depending therefrom at each side of the cow; operating mechanism operable from one side of the stall for moving the supporting means for effecting simultaneous longitudinal movement of the suspension elements; and a rigid carrying member extending transversely of the stall beneath the cow, this member being carried by said elements and being adapted to carry the milker.

11. Apparatus for supporting a suspended milker, including: a stall adapted to receive a cow; supporting means mounted at the top of the stall and movable longitudinally thereof; suspension elements immovably connected to the supporting means and depending therefrom at each side of the cow; operating mechanism operable from one side of the stall for moving the supporting means for effecting simultaneous longitudinal movement of the suspension elements; and a rigid carrying member extending transversely of the stall beneath the cow, this member being carried by said elements and being adapted to carry the milker, at least one end of the carrying member being readily removably connected to

the suspension element at such end in such manner that the connection may be readily made and separated from the opposite side of the stall, and there being means for simultaneous vertical elevation of both ends of said carrying member.
